Primary Examiner — Melanie H Tung*Assistant Examiner* — Bao-Yen Nguyen(74) *Attorney, Agent, or Firm* — Lowenstein Sandler LLP(57) **CLAIM**

The ornamental design for a display screen with an animated graphical user interface, as shown and described.

DESCRIPTION

FIG. 1 is a first view of a display screen with an animated graphical user interface.

FIG. 2 is a second view of a display screen with an animated graphical user interface.

FIG. 3 is a third view of a display screen with an animated graphical user interface; and,

FIG. 4 is a fourth view of a display screen with an animated graphical user interface.

The broken lines illustrate the display screen or portion thereof and form no part of the claimed design. The broken lines illustrate portions of the graphical user interface and form no part of the claimed design.

The appearance of the animated graphical user interface sequentially transitions between the images shown in FIGS. 1-4.

1 Claim, 4 Drawing Sheets(56)
